CLAIM

(21) Appl. No.: **29/755,487**

The ornamental design for a decorative element for a vehicle body exterior, as shown and described.

(22) Filed: **Oct. 21, 2020**

DESCRIPTION

(30) **Foreign Application Priority Data**

Apr. 29, 2020 (DE) 402020100415.4

This application contains subject matter related to the following co-pending U.S. design patent applications:
Application Ser. No. 29/702,999, filed Aug. 23, 2019 and entitled “Decorative Element for a Vehicle”;
Application Ser. No. 29/755,479, filed herewith and entitled “Vehicle, Toy, and/or Replicas Thereof”;
Application Ser. No. 29/755,480, filed herewith and entitled “Vehicle, Toy, and/or Replicas Thereof”; and
Application Ser. No. 29/755,481, filed herewith and entitled “Vehicle, Toy, and/or Replicas Thereof”.

(51) **LOC (14) Cl.** **12-16**

FIG. 1 is a front view of a decorative element for a vehicle body exterior according to the design;

(52) **U.S. Cl.**

FIG. 2 is a right, front perspective view thereof;

USPC **D12/190**

FIG. 3 is a left, bottom perspective view thereof;

(58) **Field of Classification Search**

FIG. 4 is a right side view thereof;

USPC D12/190, 181, 192, 400, 90, 91, 92, 196,

FIG. 5 is a left side view thereof;

D12/197, 198, 199, 200, 171, 172, 163,

FIG. 6 is a top view thereof;

D12/110, 114

FIG. 7 is a bottom view thereof; and,

CPC B60R 13/02; B60R 13/005; B60S 9/205

FIG. 8 is a rear view thereof.

See application file for complete search history.

The broken lines in the drawings and the lightened areas within the broken lines illustrate portions of the decorative element for a vehicle body exterior that form no part of the claimed design.
